UNITED STATES PATENT OFFICE.

JAMES ROSS, OF EAST CLEVELAND, OHIO.

TEMPERATURE-CONTROL DEVICE FOR HEATING SYSTEMS.

Application filed June 14, 1926. Serial No. 115,814.

This invention relates to a controlling device for heating systems and more particularly to a device for automatically regulating the supply of fuel to the heating unit and which is governed by the conditions existing at a given point in the system.

The main object of the invention is to provide a device of the character described which is adapted to be connected in the 10 return line of the heating unit to control the supply of fuel to the heating unit.

Another object of the invention is to provide a device of the character described which is simple and rigid in construction 15 and which is well adapted for quantity production at comparatively low cost.

Another object of the invention is to provide a control device for heating systems in which the expansion of a confined body of 20 liquid is utilized to actuate a means for diminishing the supply of fuel to the heating unit in accordance with the temperature at a given point in the system.

Further and more limited objects of my 25 invention will appear as the description proceeds and by reference to the accompanying drawing in which Fig. 1 is a diagrammatic view showing my control device connected in a heating system; Fig. 2 is an enlarged vertical sectional view of the preferred embodiment of my control device, 30 and Fig. 3 is a view similar to Fig. 2 taken at right angles thereto.

In Fig. 1 the numeral 1 designates a 35 heating unit comprising a boiler 1, a combustion chamber 2 and a cold water supply pipe 3. To the upper end of the boiler 1 is connected a pipe 4 which leads to a radiator 5 and connected with the opposite side 40 of the radiator is a return pipe 6 in which is connected my control device designated generally at 7. The fuel supply pipe 8 leads through the top of the control device 7, as shown, and the supply of fuel to the heating unit is controlled in a manner to be 45 hereinafter described.

The control device comprises a casing 9 and formed within the casing is chamber 10 having a conduit 11 leading through the 50 casing which serves as a vent and is normally closed by a plug 12. The lower end of the end of the chamber 10 is closed by a threaded cap 13 to which is connected a spring pressed plunger 14, the purpose of 55 which will hereinafter appear. A bore 15 connects with the chamber 10 and leads

through the top of the casing and is closed by a screw cap 16. Slidably mounted in the bore 15 is a valve member 17 having a stem 18 leading through an opening in 60 the top of the cap 16. The stem 18 is provided with a cap 19 which serves to limit the downward movement of the valve. The valve 17 is provided with a pair of ports 20 and 21 the purpose of which will herein- 65 after appear. Extending through the upper part of the casing, preferably at right angles to the bore 15, is a bore 22 to each end of which is connected the fuel supply pipe 8. Extending through the lower part 70 of the casing, and preferably at right angles to the bore 22 is a bore 23 to each end of which is connected the return pipe 6. From an inspection of the drawing it will be seen that the chamber 10 is formed within the 75 bore 23 and that the water returning from the radiator through the pipe 6 passes around the chamber 10 and contacts with the walls thereof.

Operation.

80

Gas or other fuel is supplied through the pipe 6 and is ignited in the combustion chamber 2 to heat the water in the boiler 1. The hot water passes up through pipe 85 4 to radiator 5 and returns to the boiler through pipe 6 and control device 7 to the boiler. The valve member 17 is normally in the position shown in Fig. 2 with the port 20 in position to allow the fuel to be supplied through pipe 8 to the combustion chamber. When the liquid in the return line and bore 23 reaches a predetermined 90 temperature the water of other fluid in chamber 10 will be correspondingly heated 95 and will expand due to the rise in temperature and will actuate the valve 17 to diminish or cut off supply of fuel to the combustion chamber. Should the water in the return line be hot enough to completely 100 close the port 20, port 21 will be opened to allow sufficient gas to pass through to ignite the pilot light. The casing is provided with an opening 24 closed by a removable plug 25 and into which a separate conduit may be connected for the pilot light, should the same be necessary.

While I have described my control device as used with a hot water heating system, my device is equally well adapted for use 105 with a steam, vapor or hot air system and I wish my invention to be limited only in

accordance with the scope of the appended claims. I also wish it to be understood that my invention is not to be limited to a control device in which water or any other liquid is used in the expansion chamber as the device will operate efficiently without a liquid in the expansion chamber. It is merely necessary to provide a sealed chamber having a piston slidably mounted there-in which will vary the rate of flow of the fuel in accordance with the temperature of the fluid adjacent the walls of the expansion chamber.

It will now be clear that I have provided a device which will accomplish the objects of the invention as hereinbefore stated.

Having thus described my invention, what I claim is:

- 20 1. A control device for heating systems comprising a casing, a fuel supply conduit leading through said casing, a liquid return conduit leading through said casing, partitions in said liquid return conduit defining a chamber, a bore connecting said chamber with said fuel supply conduit, a valve slidably mounted in said bore for regulating the supply of fuel to said heating unit in accordance with the temperature at a given point in the system.
- 30 2. In a control device for heating systems, a casing, a valve in said casing for regulating the supply of fuel to the heating unit, a liquid conduit leading through said casing, a chamber formed in said conduit adapted to be filled with liquid, said valve projecting into said chamber and adapted to be moved by the expansion of the liquid in said chamber to decrease the supply of fuel to said heating unit.
- 40 3. A thermostatic control device for heating systems comprising a casing, a fuel supply conduit extending through said casing, a liquid return conduit extending through said casing below said fuel conduit, partitions formed in said liquid return conduit defining a chamber, a bore connecting said chamber with said fuel supply conduit, a valve slidably mounted in said bore for controlling the supply of fuel to said heating unit.
- 50 4. A control device for heating systems adapted to be connected in the return line to the heating unit, comprising a casing, a bore extending through said casing the opposite ends of which are adapted to be connected with a fuel supply conduit, a second bore extending through said casing at an angle to said first bore the opposite ends of which are adapted to be connected with

a water return line, partitions formed in said last mentioned bore defining a chamber, a third bore connecting said first mentioned bore with said chamber, a valve slidably mounted in said third bore for controlling the supply of fuel to said heating unit.

55 5. A device as set forth in claim 4 in which said chamber is provided with a spring pressed plunger to take care of excess pressure in said chamber.

60 6. A thermostatic control device for heating systems comprising a valve casing, a fuel supply conduit extending through said casing, a fluid return conduit extending through said casing at an angle to said fuel supply conduit, partitions formed in said fluid return conduit defining a chamber, a bore connecting said chamber with said fuel supply conduit, a valve slidably mounted in said bore for controlling the supply of fuel through said fuel supply conduit.

65 7. A control device of the class described comprising a casing, a bore extending through said casing the opposite ends of which are adapted to be connected with a fuel supply conduit, a second bore extending through said casing at an angle to said first bore the opposite ends of which are adapted to be connected with a fluid return line, partitions formed in said second bore and defining a chamber, a third bore leading from said chamber to the outside of said casing and intersecting said first bore, a valve slidably mounted in said third bore and having one or more passageways therein and adapted to regulate the supply of fuel through said first bore in accordance with the temperature at a given point within said casing.

8. A control device operable by the force of expansion or contraction within a sealed chamber to control the supply of fuel to a heating unit and comprising a casing, a fuel supply passageway leading through said casing, said casing having a bore therein at an angle to said passageway and defining an expansion chamber, a piston arranged within the upper portion of said bore and having one or more ports therein and adapted to be actuated by the expansion or contraction of the fluid within said expansion chamber to regulate the flow of fuel through said passageway in accordance with the temperature within said expansion chamber.

In testimony whereof, I hereunto affix my signature.

JAMES ROSS.
